LIQUID DISPENSING DEVICE

Marie L. Trochim, Portland, Oreg.

Application March 4, 1947, Serial No. 732,180

4 Claims. (Cl. 128—65)

1

This invention relates to improvements in liquid dispensing devices and particularly to an improved massage device having incorporated there-in means for dispensing desired quantities of a liquid such as a lotion or tonic onto the skin or into the hair of the user while the dispenser is being used as a massage device.

Dispensers of this general type have been previously proposed but have not proved to be entirely satisfactory, the main difficulty being the lack of any means for controlling the amount of fluid applied by the device and the rate at which the fluid is applied.

Such prior art devices have also had a tendency to leak and corrode and it has been found difficult to properly maintain the flexible massage portion of the applicator in place on the body, or fluid containing compartment thereof.

It is thus among the object of the present invention to provide an improved fluid applicator and massage device having means by which the user can accurately control the amount of fluid applied by the device and in which the device is made entirely of noncorrosive materials, is leak proof and easily refillable and in which the flexible portion of the applicator is firmly attached to the rigid portion thereof in a manner such that the two portions will not become separated during the use of the device.

Other objects and advantages will become apparent from a consideration of the following description in conjunction with the accompanying drawing wherein,

Fig. 1 is a bottom plan view of the device showing in plan the flexible applicator portion;

Fig. 2 is a transverse sectional view through the device; and,

Fig. 3 is a perspective view of a control valve which regulates the amount of fluid applied by the device.

With continued reference to the drawing and particularly to Fig. 2 the applicator comprises a cup shaped receptacle, generally indicated at 10, having a flat bottom wall 11 provided with a central aperture 12 and with a surrounding annular flange portion 13.

Upstanding from the bottom wall is an annular flange or wall 14 provided externally with large screw threads 15 and having internally thereof a curved portion 16 where the annular wall joins the bottom wall 11. The flange portion 13 of the bottom wall is disposed entirely outside of annular wall 14. A cap, generally indicated at 16, has a flat transverse wall portion 17 from one side of which extends an annular flange or wall 18

2

provided with internal screw threads which fit the external threads 15 of the wall 14 of the receptacle. An annular flange or rim portion 19 surrounds the cap at the outer circumference of the transverse wall 17 and may be knurled or roughened to provide a firm hand grip when it is desired to remove or replace the cap.

A gasket or seal 20 of suitable resilient material, such as rubber, is positioned on the top of the annular wall 14 of the receptacle and is clamped between the top of this wall and the overlying portion of the transverse wall 17 of the cap to provide a liquid tight seal between the cap and receptacle.

15 A concave flexible applicator, generally indicated at 21, is provided with a thickened circumferential bead 22 having therein an internal groove 23 which receives the outer circumferential portion of the receptacle flange 13 and tightly 20 grips the outer portion of this flange in a manner such that the applicator is not easily removed from the receptacle. The material, such as soft flexible rubber, of which the applicator is made has sufficient stretch or resiliency so that the 25 bead can be applied over the flange and the two parts may be manually separated when desired, for cleaning. The applicator wall portion within the bead 22 is made relatively thin and is provided with a number of outwardly projecting 30 apertured nipples 24 through which liquid contained in the space between the applicator wall and the bottom wall 11 of the receptacle may be dispensed. Between the nipples 24 there are a number of rounded projections or knobs 25 to 35 improve the massaging action of the device.

35 A double ended valve, generally indicated at 26 and particularly illustrated in Fig. 3, is operatively positioned in the aperture 12 of the bottom wall of the receptacle. This valve member is 40 formed of suitable flexible material, such as a soft rubber, and comprises a pair of circular disc end portions 27 and 28 connected by a stem portion which may be in the form of a pair of members 29 and 30 of narrow rectangular cross section 45 crossed at right angles to each other and disposed between the adjacent surfaces of the end portions 27 and 28. It is to be understood that the members 27, 28, 29 and 30 are all integral and constitute a single valve body.

50 The width of the members 29 and 30 is somewhat less than the diameter of the aperture 12, as is clearly illustrated in Fig. 2, while the diameter of the disc like end portions 27 and 28 is somewhat greater than the diameter of the aperture. This construction provides on the inner

surface of each end portion an annular area overlying a portion of the bottom wall surrounding the aperture 12 therein. With this arrangement when either one of the end portions 27 or 28 is in contact with the adjacent surface of the bottom wall 11 it provides a seal precluding the passage of liquid through the aperture.

In using the device, when the device is held in the upright position shown in Fig. 2 and the cap 16 removed, the receptacle within the annular wall 14 may be filled with liquid and the liquid will be prevented from escaping through the aperture 12 by the seating of the end portion 27 of the valve on the bottom wall of the receptacle. The cap may then be replaced sealing the liquid in the receptacle. When it is desired to transfer liquid from the compartment within the annular wall 14 into the compartment within the flexible massage member 21 the massage member is pressed upwardly until it moves the valve to raise the end member 27 from the bottom wall of the receptacle. The liquid will then flow from the upper compartment into the lower compartment within the flexible massage member. When a sufficient amount of liquid has been transferred to the interior of the massage member the pressure on the receptacle is increased moving the massage member up further until the lower end member 28 of the valve is brought into contact with the lower surface of the bottom wall 11 of the receptacle thereby precluding any further flow of fluid through the aperture 12. The liquid in the massage or dispensing member 12 may then be dispensed through the apertured nipples 24 into the hair or onto the skin of the user. If additional liquid is desired it is only necessary to lighten the pressure on the device permitting the end member 28 of the valve to drop a slight distance below the bottom wall 11 of the receptacle thereby permitting additional fluid to flow through the aperture 12 into the flexible applicator 21.

The receptacle 10 and the cap 16 are formed of suitable noncorrosive material, such as synthetic resin, and the valve member 26 and flexible massage member or applicator 21 are formed of a type of rubber, preferably synthetic rubber, which is resistant to any oils or alcohol that may be ingredients of the fluid used in the device.

The device is thus noncorrosive and the gasket 20 provides a leak proof seal between the cap and the receptacle while the thickened bead 22 of the flexible applicator grips the flange portion of the receptacle so firmly that no leakage of fluid is permitted between the receptacle and the applicator. At the same time, the valve 26 effectively controls the flow of fluid from the receptacle into the applicator so that the desired quantity of fluid may be applied during the massaging operation.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a device of the character described a flat annular receptacle of rigid material having a flat bottom wall provided with a circumferential

flange outside of said receptacle and an aperture within said receptacle; a flanged circular closure cap for said receptacle; matching screw threads on the interior of said closure flange and on the exterior of said annular receptacle to operatively secure said closure member on said receptacle; a sealing gasket of flexible material between said closure member and said receptacle; a liquid applying member of flexible material having a circumferential bead portion secured to the circumferential flange of the bottom wall of said receptacle and a normally concave wall within said bead provided with apertured nipples for the passage of liquid from the interior of said liquid applying member; and a valve of flexible material seated within said aperture, said valve having opposite disc like end portions of a diameter sufficient to provide annular portions overlying the portion of said bottom wall immediately surrounding said aperture and a connecting portion having passages therein for the passage of liquid through said aperture from said receptacle to said liquid applying member, said valve being effective to close said aperture whenever said liquid applying member is in its extended position; and when said liquid applying member is collapsed to press the bottom end of said valve against the under surface of the bottom wall of said receptacle and to open said aperture for the passage of liquid therethrough when said liquid applying member is in a partly collapsed position in which neither end of said valve member is in contact with the bottom wall of said receptacle.

2. In a device of the character described a receptacle having a bottom wall provided with a circumferential flange and a central aperture; a closure cap for said receptacle; a concave member of flexible material overlying said bottom wall on the side thereof opposite said receptacle and having a circumferential bead firmly secured to the flange portion of said bottom wall, and apertured nipples for passing fluid therethrough; and a two ended valve member seated in said aperture and effective to close said aperture when the valve is in either its uppermost or its lowermost position and to uncover said aperture for the passage of liquid therethrough when said valve is in an intermediate position.

3. A device as defined in claim 2 wherein said receptacle is formed of a noncorrosive synthetic resin and said flexible member and said valve are formed of noncorrosive flexible material such as synthetic rubber.

4. In a manually portable device for applying a liquid to the hair or skin of the user, a rigid receptacle having a bottom wall provided with an aperture therethrough; a flexible liquid applying member secured to said bottom wall and extending over said aperture; and a double acting valve in said aperture manually operable by the application of controlled pressure to said liquid applying device to control the flow of liquid through said aperture from said receptacle to the interior of said liquid applying device.
